UNITED STATES PATENT OFFICE.

JOHN E. FIDLER, OF NEW YORK, N. Y., ASSIGNOR TO ASHER MANUFACTURING COMPANY, OF IRVINGTON, NEW JERSEY, A CORPORATION OF NEW JERSEY.

COLLAR FINISHER.

Application filed October 24, 1921. Serial No. 509,794.

To all whom it may concern:

Be it known that I, JOHN E. FIDLER, a citizen of the United States, and resident of New York, in the county of New York and 5 State of New York, have invented certain new and useful Improvements in Collar Finishers, of which the following is a specification.

This invention relates to collar finishers, 10 and more particularly to a device for finishing the fold and the adjacent inside surface of the collarband, and also if desired for finishing a surface within the fold or specifically the outer surface of the collar 15 neckband to facilitate sliding of a necktie thereover. In carrying out this invention, I provide a rotating mandrel over which the folded collar fits, and against the fold are pressed one or more stationary and preferably heated ironing shoes. The operator 20 places a shaped collar on the mandrel, which carries it under the shoes, after which the operator removes the collar on the other side. The mandrel is large enough to accommodate two collars at a time, so that 25 the operator, while removing the finished collar with one hand, puts on the next collar with the other hand, and without stopping rotation of the mandrel. As the tab 30 of the collar projects above the plane of the folded edge, it is deflected from between the shoes and the mandrel, this being accomplished by a bevel on the shoe which prevents the tab from being bent or folded 35 down. The shoe is pressed against the collar by a spring, which may be adjusted, and the shoe is heated by electricity or other means. For finishing the outside of the neckband so that a necktie will slide more 40 easily, there is provided a drum within the mandrel rotating at a different speed, so as to operate simultaneously with the fold and inside neckband ironing shoes.

With these and other objects in view I 45 have devised the apparatus embodying my invention as described in the following specification and illustrated in the accompanying drawings, of which—

Figure 1 is a plan view of the device; 50 Figure 2 is a section taken on the line 2—2 of Figure 1; Figure 3 is a section taken on the line 3—3 of Figure 1, and Figure 4 is a section of a simpler form

wherein the collarband outside finisher is 55 omitted.

Referring to Figs. 1 to 3 of the drawings, 1 indicates the frame of the machine bolted through a bottom flange 2 to a table or other means of support 3. Mounted in bearings 4 in frame 1 is shaft 5, having keyed upon its outer end drive pulley 6 which is connected by belting to a suitable source of power, or direct driven from a motor. Secured on shaft 5 is a worm 7 which runs between a pair of bearings 4, and drives worm wheel 8 secured to shaft 9 running in bearings 10 in housing 1. Secured to shaft 9 is mandrel 11 having a smooth finished edge 12. Pivottally mounted on bracket 13 secured to housing 1 is inner shoe 14, the same being pivoted to bracket 13 on pin 15; and being composed of metal or other suitable heat conducting material. Shoe 14 bears on the fold as well as on the inside of the neckband to iron same, ordinarily for about one half inch down from the fold. Spring 16 mounted on bolt 17 threaded in shoe 14 exerts compression between nut 18 on bolt 17 and washer 19 on bracket 13 tending to draw shoe 14 downwardly about pivot 15, said pressure being adjustable by varying the position of nut 18. Mounted in lug 20 in bracket 13 is stop bolt 21, which 70 limits the movement of shoe 14 by contacting with the end of bolt 17, stop bolt 21 being adjustable and being held in any given position by lock nut 22. Shoe 14 extends over the edge 12 of mandrel 11 and has a finished surface 23 adapted to bear 75 in a direction parallel to the mandrel axis against edge 12, and surface 46 to bear on the inside of the neckband. The portion of shoe 14 within mandrel 11 extends below the edge 12 and is cut away as at 24 to provide annular clearance for the inside edge of mandrel 11. A depression 25 is formed in the inner face of shoe 14 and into this depression 25 is directed a jet from burner 26, the latter being protected by a housing 27 connected and secured to bracket 13, and burner 26 being supplied through pipe 28 which connects with supply pipe 29. A pair of outside shoes 30 are positioned on each side of finisher 14 and are similar thereto and have similar finishing surfaces 24, but the body of each of shoes 30 is positioned outside of mandrel 11. Shoes 30 are beveled 80 85 90 95 100 105

on their ends as at 47 to deflect the collar tab, if it is of the locking type projecting above the plane of the mandrel, and also extend below edge 12 and are similarly cut 5 away to provide annular clearance. Shoes 30 have depressions 25 which are heated by burners 31 supplied by pipes 32 which connect with supply pipe 29, and are guarded by housings 33 connected to bracket 13, and 10 preferably integral with housing 27. Shoes 30 are mounted on bracket 13 by pivots 15 and are held in position by springs 17 on bolts 16 and adjusted by stop 21 in the same manner as shoe 14.

15 In the form shown in Figure 2, a neckband polishing drum 34 for the outer surface of the collar neckband is within mandrel 11 and mounted on shaft 35, the latter being carried inside of shaft 9 which is 20 made hollow for the purpose. Adjacent worm wheel 8 on shaft 9 and securely fixed to the latter, is spur gear 36, which meshes with spur gear 37 on countershaft 38 carried in bearings 39 in housing 1; and adjacent gear 37 on countershaft 38 is mounted spur gear 40 meshing with spur gear 41 securely fixed on shaft 35, and thereby driving drum 34. Shaft 35 is continued below gear 41 and extends through bearing 42 in housing 1. Shaft 9 is held against endwise movement by a shoulder 43 on housing 1, which cooperates with a similar surface on the adjacent portion of mandrel 11 and constitutes a thrust bearing which carries 25 the weight of mandrel 11 and of shaft 9. Drum 34 and shaft 35 are similarly supported by shoulder 44 on boss 45 on mandrel 11. Gear 37 has a greater pitch diameter than gear 36, and gear 41 has a greater pitch diameter than gear 40, so that drum 34 will be driven at less speed than mandrel 11. Upper edge 45 of drum 34 is below edge 12 and so does not extend all the way 40 to the fold of the collar, which is thus carried at the speed of mandrel 11, and drum 34, owing to its slower speed, will thus 45 polish the outer surface of the neckband.

50 The collar is slid over the mandrel against edge 12, which fits into the fold. The tab of the collar will, in some styles, project slightly above the plane of edge 12, and shoes 30 are beveled to deflect the tab as the collar passes under the shoes. Bevels such as 47 deflect the tab laterally. Surfaces 23 on the shoe 14 are bevelled away at each end so as to ride over the fold of the collar on mandrel 11 and depress the tab downwardly, the collar yielding sufficiently to permit the tab to be pressed down 55 below or flush with the top surface of the mandrel.

60 If desired, the neckband finishing feature may be omitted, and the construction accordingly modified by making shaft 9 solid and by omitting drum 34, shaft 35, gears 41

and 42, countershaft 38 with its bearings 39, and gears 37 and 40, as shown in Figure 4.

The operation of the device will be apparent from the foregoing description. 70 Collars may be placed on mandrel 11 while in motion, and the operator very quickly acquires the knack of placing on a fresh collar with one hand while removing the finished collar with the other, without stopping rotation. The machine will operate in either direction, but preferably is so driven that the tab end is last, as a locking type projecting tab will deflect more easily.

75 The bevels 47 deflect the tab laterally and prevent it being folded under the shoes 30. Since the surface 23 of shoe 14 is bevelled away at each end, as stated above, this prevents the tab being folded over by shoe 14 since the bevels at its ends push the tab 80 down below the edge 12 instead of bending it over. The tab of a collar is generally an extension of the inner half or the portion here designated as the collar neckband so that the tab is on the inside of mandrel 11 85 and projects slightly above the edge 12. It will then be clear how the bevels 47 prevent the tab from getting under the shoes 30 regardless of the direction of rotation of mandrel 11 and regardless of whether the tab be at the front or rear of the moving collar. In order for the drum 34 to 90 finish a surface of the collar within the fold, that is, the outer surface of the collar neckband or the outer surface of the inner half of the collar, it will appear from Fig. 2 that this collar neckband or inner half of the collar must be engaged between drum 34 and shoe 14. Shoe 14 polishes the fold and inner surface of this collar neckband 95 or inner half of the collar while drum 34 polishes the outer surface of this neckband or the portion of the collar within the fold which is in contact with the necktie, so that the necktie may slide more easily within the fold. Besides ironing the fold and inner surface of the neckband or inner part of the collar, shoe 14 also functions to press this portion of the collar against the finishing drum 34.

100 This machine gives a much greater output than machines heretofore devised for this purpose, with less effort by the operator.

105 What I claim is:

110 1. In a collar ironing machine the combination with a rotatable mandrel for holding a folded collar, of means rotatable relatively to the mandrel for finishing a surface of the collar within the fold while the collar is carried by said mandrel, means resiliently pressing the collar and finishing means against one another while the collar is carried by the mandrel.

115 2. In a collar ironing machine, the combination with a mandrel for carrying a fold-

ed collar by supporting the same under its fold, of a polishing drum concentric with said mandrel and having its upper edge below the top of said mandrel for finishing 5 the outer surface of the collar neckband, means for producing relative rotation between said mandrel and drum, and means on the other side of said drum from the mandrel for pressing the surface of the 10 collar to be finished against said drum.

3. A collar finisher comprising a mandrel adapted to receive a folded collar, finishing means which comprises a plurality of ironing shoes, one in cooperation with the 15 top of the fold and one side of the collar, and another arranged to cooperate with the top of the fold and the other side of the collar during the ironing operation.

4. A collar finisher, comprising a mandrel 20 to receive a folded collar, a drum within said mandrel to fit within the fold of the collar, the edge of said drum terminating short of the edge of said mandrel and the inner surface of said drum contacting with 25 the outer surface of the collar neckband, and means for rotating said mandrel and drum in relation to one another.

5. A collar finisher, comprising a mandrel 30 to receive a folded collar, a drum within the mandrel to fit within the fold, the edge of said drum terminating short of the edge

of said mandrel and the inner surface of said drum contacting with the outer surface of the collar neckband, finishing means bearing against the fold, means for rotating said mandrel to carry the collar under the finishing means and away therefrom, and means for rotating said drum at a different velocity from said mandrel. 35

6. In a collar ironing machine, the combination with a mandrel rotatable in fixed position, of an ironing shoe for cooperation therewith, a supporting frame for said mandrel and shoe, means engaging said frame for pressing said shoe against the 40 top and a substantial portion of a side of a collar carried by the mandrel for ironing the same, means for mounting the shoe on said frame whereby the same is yieldable toward and from both the top of the 45 fold and the side of the collar and for mounting said shoe relatively stationary with respect to the frame except for its yieldability to fit different thicknesses of 50 collars, and means for limiting said pressing means and controlling the separation of 55 the shoe and mandrel.

Signed at New York, in the county of New York and State of New York October A. D. 1921.

JOHN E. FIDLER.
